Des. 133,165

UNITED STATES PATENT OFFICE

133,165

DESIGN FOR A RUG

Olga C. Van Antwerp, Crichton, Ala.

Application May 21, 1942, Serial No. 106,964

Term of patent 3½ years

To all whom it may concern:

Be it known that I, Olga C. Van Antwerp, a citizen of the United States, residing at Crichton, in the county of Mobile and State of Alabama, have invented a new, original, and ornamental Design for a Rug, of which the following is a specification, reference being had to the accompanying drawing, forming part thereof.

I claim:

The ornamental design for a rug, as shown.

OLGA C. VAN ANTWERP.
